UNITED STATES PATENT OFFICE.

FRANK L. WRIGHT, OF CHICAGO, ILLINOIS, ASSIGNOR TO THE LUXFER
PRISM PATENTS COMPANY, OF SAME PLACE.

DESIGN FOR A PRISM-PLATE.

SPECIFICATION forming part of Design No. 28,011, dated December 7, 1897.

Application filed October 23, 1897. Serial No. 656,238. Term of patent 14 years.

To all whom it may concern:

Be it known that I, FRANK L. WRIGHT, a citizen of the United States, residing at Chicago, in the county of Cook and State of Illinois, have invented a certain new and original Design for Prism-Plates, of which the following is a description.

My invention relates to designs for prism-plates.

10 Figure 1 is a plan view of a prism-plate embodying my design. Fig. 2 is a section therethrough with parts broken away and enlarged.

15 A is the body of the prism-plate; B B, a series of surface areas formed on one side thereof by the lines of separation C C. These surface areas are substantially uniform.

D D are prisms on one side of the plate,

and E E prisms on certain of the surface areas grouped about the center, so as to form a sort of central-surface prism or decorated part. 20

The essential features of my design are found in a prism-plate comprising a substantially flat extended body with surface areas on one side formed by means of lines of separation, prisms on the other side, and prisms 25 in a body of such surface areas gathered about the center.

I claim—

A design for a prism-plate, substantially as shown and described.

FRANK L. WRIGHT.
